UNITED STATES PATENT OFFICE.

FRED H. DANIELS, OF WORCESTER, MASSACHUSETTS.

HEAT-RETAINER.

941,858.

Specification of Letters Patent. Patented Nov. 30, 1909.

Application filed January 21, 1909. Serial No. 473,482.

To all whom it may concern:

Be it known that I, FRED H. DANIELS, of Worcester, Worcester county, Massachusetts, have invented a new and useful Improvement 5 in Heat-Retainers, of which the following is a full, clear, and exact description, reference being had to the accompanying drawings, forming part of this specification, in which—

10 Figures 1 and 2 are respectively horizontal and vertical longitudinal sections of the preferred form of heat retainers, and Fig. 3 is a cross section on the line III—III of Fig. 1. Fig. 4 is a plan view partially in section 15 of a modified form of heat retainer; Fig. 5 is a side elevation thereof, partially in section; Fig. 6 is a sectional view on the line VI—VI of Fig. 4; Figs. 7 and 8 are respectively horizontal and vertical sectional 20 views, of another modified form of heat retainer; Fig. 9 is a sectional view on the line IX—IX of Fig. 8.

My invention has relation to heat retainers for use in rolling mills.

25 The object of the invention is to provide a chamber, in which flat bars of long lengths, having passed the so-called roughing part of a rolling mill, may be stored for a certain period of time, and heat so applied and regulated that the bars will have the right uniform temperature throughout their whole length before they are passed into the next or finishing part of the mill. The heat retainer also provides for a convenient means 30 of disposing of bars from the roughing mill in case the finishing mill should cobble or suddenly get out of order, and which, without the retainer, would have to be run out on the floor and become scrap. The retainer 35 may be of any suitable design depending upon the fuel used and the maximum length of the billets adopted.

The precise nature of my invention will be best understood by reference to the accompanying drawings, which will now be described, it being premised, however, that various changes can be made in the details of construction and arrangement, by those skilled in the art, without departing from 45 my invention, as defined in the appended claims.

In the drawings, the letter B designates the heat retainer, which, as shown in Figs. 1, 2 and 3, preferably has a number of trough-shaped channels 2 made up of fire brick and are provided with passages 3 between the

channels to permit the free circulation of gases around the channels. These channels are arranged one above the other, so that a number of flats may be resting in the heat 60 retainer B at the same time. I have shown in these figures four of these trough-shaped channels, but any number desired may be used. The lower layer of bricks rest on water-cooled pipes, 4, thus providing ample 65 structural strength with minimum obstruction for the hot gases. The retainer has openings 5 in the sides thereof for the admission of the gas from the burners, which passes up and around the bars in the channels 70 2, and then out through the flues 6. At each end of the retainer B are movable feed rolls 7 and 8 which are movable bodily up and down for feeding in and withdrawing flats or bars from the channels 2. These movable 75 feed rolls have feed tables 9 and 10 attached thereto and are swung up or down by any suitable means. It is obvious that where only one channel 2 is required, the rolls 7 and 8 and tables 9 and 10 need not be movable. At the ends of the retainer B are 80 openings 11 and 12 through which suitable gripping tongs or other tools may be inserted to move the hot bars.

In the modification shown in Figs. 4, 5 85 and 6, I have shown a retainer in which the feed rolls 35 can be stationary. The flats X are delivered from the roughing mill, to the heat retainer B through one end and side thereof by means of the feed rolls 35. The 90 flats are fed into the heat retainer one on top of the other, two to four high. The opening from the heat retainer to the finishing mill is at the other end and side thereof. The pile of flats is pushed from one side of 95 the heat retainer to the other side, by means of power operated plungers 36, and are fed to the finishing mill over the stationary feed roll 38. The plungers 36 can be operated by hydraulic cylinders or any other available means.

In the modification shown in Figs. 7, 8 and 9, the flats X are fed into one end of the heat retainer B, by the stationary feed rolls 35, and are fed to the finishing mill 105 from the other end thereof, by means of the roll 38. The flats are delivered to the heat retainer one on top of another, from the roughing mill. The bottom piece is pushed out through the delivery end of the retainer 110 by means of a ram 37, the engaging end of the ram is provided with a projection 39

whose upper end is slightly below the upper edge of the bottom flat. The delivery end of the retainer is provided with a guard 40, whose lower edge is slightly above the upper 5 edge of the bottom flat. Thereby, insuring the engagement of only one flat by the ram, and by means of the guard, preventing the drawing of the second flat by frictional contact. The heat in the retainer is not sufficiently high to cause the slabs to stick together. The retainer may be fired with oil, 10 gas, coal or any other suitable fuel.

From the foregoing description of my apparatus, it will be seen that my heat retainer is used in conjunction with a mill for rolling flats in the following manner. The billet is first elongated by passing it through a roughing mill, from which the flats or other shapes are passed onto the movable 15 feed rollers 7. The flats are fed in rotation by means of the feed rollers into the various channels 2 in the heat retainer B, and are withdrawn likewise in rotation, by means of the rollers 8, from which they are fed to the 20 finishing rolls. The advantages of my invention result from the provision of a heat retainer to receive the flats after they pass from the roughing rolls, and before they 25 pass to the finishing rolls, whereby heat can be so applied that the bars or flats will 30 have the proper and uniform temperature throughout their length, when fed to the finishing mill. Also in providing a heat retainer in which a series of flats can be 35 stored between the roughing and finishing mills, thereby providing a convenient means for disposing of flats from the roughing mill if the finishing mill should get out of order, and also providing storage space from which 40 the finishing mill can be supplied with flats if the roughing mill should be shut down for a short period.

I claim:—

1. A heat retainer for metal shapes, comprising a furnace, a support of refractory material to receive the shapes one above another in the same vertical plane, means to feed the shapes to the support, and means to withdraw the shapes from the support, 45 substantially as described.

2. A heat retainer for metal shapes comprising a furnace, a support of refractory material to receive the shapes one above another, openings through the sides of one of 55 the furnace walls at the ends thereof for access to said shapes, means to feed the shapes to the support, and means to withdraw the shapes from the support; substantially as described.

3. A heat retainer for metal shapes, comprising a furnace, a plurality of longitudinal supports of refractory material in different horizontal planes extending 60 through the furnace, adjustable means for feeding the shapes successively to one end of

the supports, and adjustable means for successively withdrawing the shapes from the other end of the supports; substantially as described.

4. A heat retainer for metal shapes, comprising a furnace, a plurality of longitudinal supports of refractory material extending through the furnace, openings through the sides of one of the furnace walls at the ends thereof for access to said flats, means for 70 feeding the shapes successively to one end of the supports, and means for successively withdrawing the shapes from the other end of the supports; substantially as described.

5. A heat retainer for metal shapes, comprising a furnace, a plurality of trough shaped longitudinal supports one above another of refractory material extending through the furnace, means for feeding the shapes successively to one end of the supports, and means for successively withdrawing the shapes from the other end of the supports; substantially as described.

6. A heat retainer for metal shapes, comprising a furnace, a plurality of longitudinal supports one above the other of refractory material extending through the furnace, a water-cooled support for the lower supports, means for feeding the shapes successively to one end of the supports, and means for successively withdrawing the shapes from the other end of the supports; substantially as described.

7. A heat retainer for metal shapes, comprising a furnace, a plurality of longitudinal supports one above the other of refractory material extending through the furnace, a water-cooled support for the lower supports, circulating passages between the supports, means for feeding the shapes successively to 90 one end of the supports, and means for successively withdrawing the shapes from the other end of the supports; substantially as described.

8. A heat retainer for metal shapes, comprising a furnace having a plurality of parallel supports, means on said supports for guiding the shapes, and feeding and withdrawing mechanism for feeding the shapes to and withdrawing them from any 100 one of said supports; substantially as described.

9. A heat retainer for metal shapes, comprising a furnace having a plurality of parallel supporting guides one above the other, and vertically adjustable feeding and withdrawing mechanism for feeding the shapes to and withdrawing them from any 110 of said guides; substantially as described.

10. A heat retainer for metal shapes, comprising a furnace having a plurality of parallel supporting guides one above the other, circulating passages between the supporting guides, and vertically adjusting feeding and withdrawing mechanism for 120 130

feeding the shapes to and withdrawing them from any one of said guides; substantially as described.

11. A heat retainer for metal shapes, comprising a furnace, a support to receive the shapes one above another, means to feed the shapes successively to the furnace, and means to successively withdraw the shapes therefrom; substantially as described.

10 12. A heat retainer for metal shapes, comprising a furnace, a support to receive the shapes in different horizontal planes, a receiving opening at one end of the furnace and a delivery opening at the other end thereof; substantially as described.

15 13. A heat retainer for metal shapes, comprising a furnace, a support to receive the shapes in different horizontal planes, a receiving opening at one end of the furnace, a delivery opening at the other end, means to feed the shapes successively to the furnace, and means to successively withdraw the shapes therefrom; substantially as described.

14. A heat retainer for metal shapes, comprising a furnace, a support to receive the shapes one above another, a receiving opening at one end of the furnace, a delivery opening at the other end, means to feed the shapes successively to the furnace one above another, and means to successively withdraw the shapes therefrom; substantially as described.

15. A heat retainer for metal shapes, comprising a furnace having a plurality of parallel supports, one above another, means for guiding the shapes on said supports, and feeding and withdrawing mechanism for feeding the shapes to and withdrawing them from any one of said supports; substantially as described.

In testimony whereof, I have hereunto set my hand.

FRED H. DANIELS.
